UNITED STATES PATENT OFFICE

101,684

DESIGN FOR A LOUDSPEAKER HORN

Clyde E. Sweeny, Toledo, Ohio

Application May 1, 1936, Serial No. 62,414

Term of patent 7 years

To all whom it may concern:

Be it known that I, Clyde E. Sweeny, a citizen of the United States and resident of Toledo, county of Lucas, State of Ohio, have invented a new, original, and ornamental Design for a Loudspeaker Horn, of which the following is a specification, reference being had to the accompanying drawing, forming a part thereof.

In the drawing, Fig. 1 is an end elevation of a loudspeaker horn embodying my new design, and Fig. 2 is a side elevation thereof.

The dominant feature of the design resides in the bell-like members which are each substantially alike and have their inner ends merging together, combined with a grille surrounded by a bezel located between the bell-like members, so as to present the same appearance when viewed from either the front or rear thereof, as shown.

I claim:

The ornamental design for a loudspeaker horn, substantially as shown and described.

CLYDE E. SWEENEY.
